DISPLAY CASE

Thomas J. Pilliod and Ferdinand C. H. Müller,
Swanton, Ohio, assignors to The Pilliod Cabinet Company, Swanton, Ohio, a corporation of Ohio

Application October 20, 1937, Serial No. 169,994

1 Claim. (Cl. 217—56)

This invention relates to merchandise display cases, and particularly to transparent closure members for the display openings of such cases.

The object of the invention is the provision in a case of this character of a closure member of resilient material preferably, but not necessarily, of a transparent nature, having depending marginal flanges together with simple and novel means for engaging such flanges to the side wall members of a display opening of the case.

Further objects and advantages of the invention will be apparent from the following detailed description and from the accompanying drawing, in which—

15 Figure 1 is a vertical cross-sectional view of a display case, with closure members embodying the invention in association with both the cover and bottom members thereof, and Fig. 2 is an edge elevation of one of the closure members shown in Fig. 1, as it appears when removed from the case.

Referring to the drawing, 15 designates the cover of an article display case, which cover has its under side recessed, and 16 designates the bottom or body member of such a case and has its top side recessed to receive articles to be displayed. The bottom member 16 is shown as provided with the customary lining member 17 which projects at its outer edge above the edge of the case member to adapt it to enter within the edge of the recess in the cover member 15. Such lining is customarily faced with a soft cloth, or other suitable material 18. A closure member 19 embodying the invention is mounted in each member 15, 16, of the display case and each of such members is of resilient material preferably, but not necessarily, transparent. This material may constitute what is termed in the trade as "acetate sheet", or it may be of cellulosic, or other suitable nature. The former is non-combustible and therefore preferable to use.

Each closure member 19 is of polygonal shape and size corresponding substantially to the shape and size of the recess of the case member in which it is disposed, and is provided, preferably at each edge, with a flange 20 projecting laterally from the body portion of the member in angular relation thereto, and when in such position to have its end edges substantially meet with those of adjoining ends. The flanges 20 normally stand in outwardly sprung relation to the positions they assume when mounted in the case member, as shown in Fig. 2. The outer edge of each flange 20 is provided with an integral outturned lip flange 21 which is shown as in-

clined outwardly from the flanges toward the plane of the body portion of the closure member.

When a member 19 is inserted into the recess or opening of either the cover 15 or bottom 16 of the case, the edge flanges 20 are pressed inwardly from their normal outwardly sprung positions and the free edges of the lip flanges 21 bear outwardly against the side walls of the recess and serve to frictionally resist a withdrawal of the closure member from the recess. The body portion of the member 19, which is disposed within the case member 16, is substantially the size of the recess so as to fit therein, while the member 19, which is disposed in the cover member, is slightly smaller in size than the recess 15 of the cover member, so as to receive the outwardly projecting edge of the lining 17 when the cover member is closed down over the bottom member 16, as shown in Fig. 1.

The lip flanges 21 are acutely angled relative 20 to the attached flanges 20, so as to facilitate telescoping the closure 19 within a respective case member and then to coat at their edges with the wall of the recess in which disposed to resist an outward withdrawal thereof from the member. 25

It is apparent that in shaping a closure member embodying the invention, the material comprising such member is preferably of such a nature that the best results would be obtained by subjecting the member to heat during the pressing or shaping operation.

We wish it understood that our invention is not limited to any specific construction, arrangement or form of the parts, as it is capable of numerous modifications and changes without departing from the spirit of the claim.

Having thus described our invention, what we claim as new, and desire to secure by United States Letters Patent, is:

In a display case, a member having side walls 40 and an open top, and a closure member of thin material of a resilient nature for closing said opening, said member having depending normally outwardly sprung flanges adapted, when retracted from normal position, to be telescoped 45 within said side walls through said opening and having outwardly turned edge lips which frictionally engage the respective side wall surfaces, said lips being acutely angled relative to the attached flanges to facilitate insertion of the closure member into said member and to resist an outward withdrawal thereof from the member.

THOMAS J. PILLIOD.

FERDINAND C. H. MÜLLER.
